 ATTORNEY

UNITED STATES PATENT OFFICE.

CHARLES J. PALM, OF NEWARK, NEW JERSEY.

DEVICE FOR HOLDING PIANO-COVERS TO PIANOS.

1,358,239.

Specification of Letters Patent. Patented Nov. 9, 1920.

Application filed March 22, 1918. Serial No. 223,902.

To all whom it may concern:

Be it known that I, CHARLES J. PALM, a citizen of the United States, residing in the city of Newark, in the county of Essex and State of New Jersey, have invented certain new and useful Improvements in Devices for Holding Piano-Covers to Pianos, of which the following is a full, clear, and exact description, such as will enable others skilled in the art to which it appertains to make, construct, and use the same, reference being had to the accompanying drawings, and to characters of reference marked thereon, forming a part of this specification.

15 My invention relates to curtain supports for a piano, the object being to provide in such a support, features of construction whereby a curtain may be easily applied to or removed from its support; which shall 20 be easy of manipulation and removal; shall be capable of being made in an inexpensive manner according to desire or taste. A further object of this invention is to furnish a support and cover or curtain for upright 25 pianos by which the upper part or the entire piano is inclosed in such a manner that it does not interfere with the sound of the instrument, and which has at the same time a very ornamental and attractive appearance.

30 Referring to the accompanying sheet of drawings, in which I have illustrated one preferable embodiment of my invention, I will proceed to describe the same, having 35 it understood that I am not limited to the specific details of construction shown and described, as it is manifest that these may be modified and changed without departing from the spirit or scope of the invention.

40 Figure 1 represents a plan view, partly in section, of the preferred embodiment of my invention, secured to the cover of a piano with the curtain removed.

45 Fig. 2 represents a sectional side elevation taken on line $x-x$ of Fig. 1.

Figs. 3 and 4 represent respectively a plan view and a side elevation of the adjustable bracket for the curtain support, and,

50 Fig. 5 represents a fragmentary perspective view of the curtain support and curtain secured to the cover of a piano.

In the drawings, I have shown a support which may consist of a single rod or tube, or as shown, said support being preferably made telescopic so as to be adjustable to

50 pianes of different lengths and widths, and which comprises two telescopic sections numbered 1 and 2. Secured to the rear of the piano in any desired or convenient manner, and preferably to the lid or cover of the same, are brackets 3—3, each bracket preferably made from a single piece of rod or tube, one end of which is flattened to provide a base or foot 4 which may be provided 55 with one or more screw holes so that the bracket may be secured to the back of the piano or cover.

Any suitable means may be provided to 60 secure a friction fastening for the curtain support and bracket to hold the same in adjusted and operative position. In the present instance I may provide a screw 5 in the ends of the tubes 1 and 2 which engage with the free ends of the brackets 75 3—3 as clearly indicated in the drawings. This construction makes it a comparatively 65 easy matter to attach the support to the lid, cover or back of a piano, and then to 70 adjust it to the desired length and width 80 of the piano.

In order to provide a simple, inexpensive, 75 adjustable and readily removable supporting device for the curtain support, I employ two members numbered 6 and 7, adjustably 85 secured together in any desirable manner, preferably by means of a slot 8 provided in the member 6 and a stud 9 and a nut 10 carried by the member 7 as hereinafter 90 described. The members 6 and 7 of the supporting device are preferably made from flat sheet metal, the member 6 being provided with an offset portion 11 designed to 95 engage with the rear of the piano cover or lid 12 and the member 7 is also provided with 100 an offset portion 13 to engage with the front of the piano cover or lid and by means of which said supporting device is adjustably 105 secured to said lid or cover. The offset portion 11 and 13 of the members 6 and 7 may have a shape corresponding to the shape of 110 the edge of the piano cover or lid 12, with which they engage. By means of the slot 8 formed in the member 6 and the stud 9 and nut 10 carried by the member 7, it is readily 115 understood how said members can be removably secured to the piano cover or lid without the use of screws or the like. The member 6 is further provided with an adjustable receiving element 14, designed to receive 110 and support the curtain support, formed by doubling the metal of the member 6 in the

manner illustrated and securing it together by means of a screw 15 or the like. The receiving element 14 is preferably shaped to conform to the shape of the telescopic sections 1 and 2.

By any of the well known fastening devices a curtain or the like, may be slidably secured to the curtain support by which the upper part or the entire piano is inclosed in 10 such a manner as not to interfere with the sound of the instrument, and which has at the same time a very ornamental and attractive appearance. The adjustable support, as previously stated is made from ordinary 15 sheet metal and the parts are of such shapes as to lend themselves readily to manufacture by the use of ordinary tools and dies.

Experience has demonstrated that the organization above described is a highly 20 efficient one, and while the device described is the preferred embodiment of my present invention, I do not care to restrict myself to the exact details of construction, combination and arrangements herein set forth, it 25 being obvious that minor variations thereof, not involving the exercise of invention, may be made by any skilled mechanic, and such departures from what is herein described and claimed, not involving invention I consider within the scope and terms of my 30 claims.

Having now described my invention, what I claim as new, and desire to secure by Letters Patent, is:

35 1. In a device of the character described,

the combination of a tubular curtain support, brackets in engagement with the ends of said curtain support and secured to the cover of a piano, and a bracket comprising two members adjustably secured together, 40 the ends of said members engaging the front and rear edges of the piano cover, one of said members being further provided with a receiving element to hold the curtain support in adjusted and operative position. 45

2. In a device of the character described, the combination of a tubular curtain support, comprising two telescopic sections, brackets secured to the cover of the piano in engagement with the ends of said tubular 50 sections, means for adjusting the ends of said sections relative to said brackets and an adjustable clamping bracket secured to the front and rear edges of said piano cover designed to clamp the said curtain support in 55 adjusted and operative position, said clamping bracket comprising two members slidably secured together, the ends of said members engaging the front and rear edges of the piano cover, the front member being provided with an adjustable receiving element to hold the curtain support in adjusted and operative position.

This specification signed and witnessed this 26th day of December, 1917.

CHARLES J. PALM.
